SIGNAL LIGHT HOUSING

Charles L. Craddock, Burbank, Calif., assignor to Michael Research Company, Inc., Burbank, Calif., a corporation of California

Original design application Aug. 3, 1966, Ser. No. 3,325,
now Patent No. 209,537, dated Dec. 12, 1967. Divided
and this application Apr. 26, 1967, Ser. No. 7,962

Term of patent 14 years

Int. Cl. D26—04

U.S. Cl. D48—24

Fig. 1

Fig. 2

Fig. 3

FIG. 1 is a perspective view of a signal light housing showing my new design;

FIG. 2 is a side elevational view;

FIG. 3 is an end elevational view;

FIG. 4 is a perspective view of a modified form of my design;

FIG. 5 is a side elevational view of the modified form; and

FIG. 6 is an end elevational view thereof.

This is a division of design application Ser. No. 3,325, filed Aug. 3, 1966, now design Pat. No. 209,537, issued Dec. 12, 1967.

The characteristic features of my design for the signal light housing disclosed, reside in the specific construction of the head member, as best shown in FIGS. 3 and 6.

I claim:

The ornamental design for a signal light housing, substantially as shown.
